(57) **CLAIM**

The ornamental design for a washing, deburring and drying machine for machined parts, as shown and described.

DESCRIPTION

1. Washing, deburring and drying machine for machined parts

2. Washing, deburring and drying machine for machined parts

1.1: Perspective

1.2: Perspective

1.3: Front; the rear view is a mirror image of the front view.

1.4: Left

1.5: Right

1.6: Top

2.1: Perspective

2.2: Perspective

2.3: Front; the rear view is a mirror image of the front view.

2.4: Left

2.5: Right

2.6: Top

2.7: Cross sectional

2.8: Reference view

Fig. 2.8 is a reference view showing the state in which the access doors are open; the hatching shown in the fig. 2.8 indicates transparency and the lines of the hatching them-
